FIG. 3

Inventor:
John Hines
By Kent W. Wonnell Atty.

UNITED STATES PATENT OFFICE.

JOHN HINES, OF LONDON, ENGLAND.

MEANS FOR MAKING AND REPAIRING ROADS AND LIKE SURFACES.

Application filed September 5, 1925. Serial No. 54,615.

To all whom it may concern:

Be it known that I, JOHN HINES, a subject of the King of Great Britain, of 4 Prince's Mansions, 70 Victoria Street, London, S. W. 1, England, have invented certain new and useful Improvements in Means for Making and Repairing Roads and like Surfaces, of which the following is a specification.

- 10 This invention relates to improvements in means for making and repairing roads and like surfaces, and has for its object to overcome the disadvantages inherent to the use of an ordinary roller for rolling a surface 15 layer of heated tar or bitumen, and more particularly cold tar macadam, on to a road surface.

The ordinary roller as at present used is at atmospheric temperature which in winter 20 may be at freezing point, and the roller chills the surface layer of tar, bitumen, or the like causing it to contract away from the road bed and preventing the adhesion of the surface layer to the road bed which is 25 essential if the road is to be lasting under modern traffic.

In accordance with my invention I arrange for a roller to be heated to any desired temperature by directing hot air or gases 30 around the outer surface of the roller so that the roller and the road surface are heated simultaneously, and a lasting and homogeneous surface layer is produced on the road.

35 By way of example one practical form of my invention has been illustrated in the accompanying drawings in which:—

Figure 1 is a side elevation of the complete machine.

40 Figure 2 is a plan.

Figure 3, a transverse section on an enlarged scale through the axis of the roller.

In the form illustrated the machine embodying my invention consists essentially 45 of a steam or other wagon similar in construction to an ordinary road roller, but having its main chassis members *a* considerably extended to the rear to support the furnace *b* and roller *c* which takes the place of the usual rear wheels of the roller.

The front of the machine may be supported by a pair of wheels *d* as shown arranged to swivel about an axis *e* and controlled through a segment *f* and worm *g*

55 from a steering wheel *h* in the usual manner.

Alternatively the wheels *d* may be replaced by a roller as in the known type of machine, as this enables the machine to be steered more easily and used right up to the edge of a road. Also any chilling effect of the front 60 roller on the road surface is immaterial when it is followed by the thorough heating of the surface as described below.

The roller *c* is mounted in bearings *j* on the side members *a* of the chassis and is 65 driven by chain from the engine counter shaft *k*, the usual tensioning means *l* being provided for adjusting the tension of the driving chain.

The roller is wholly enclosed within a 70 sheet metal casing *m* mounted on the rear end of the chassis and forming a hood which extends downwardly practically to the road surface, the lower edges of the hood being formed by hinged flaps *n* which can be 75 raised up for travelling or to control the escape of hot air and gases, and evaporated moisture from the road surface. Within the hood behind the roller is the furnace *c* fed through a door at one side and the hood 80 above the furnace is curved upwardly and forwardly as shown at *p* to provide a chamber in which combustion of the fuel is completed and to induce a natural flow of the heated air and gases. The front part of the 85 curved top of the hood and the part above the roller are preferably lagged as shown at *o* to minimize loss of heat.

A powerful fan *q* is mounted at the rear 90 end of the hood and is driven by a small high-speed engine *r* mounted above the roller. Where the roller is steam driven this engine may conveniently be a steam engine supplied with steam from the main boiler.

The fan delivers a large volume of air 95 into the furnace, above and below the bars in proportions controlled by a damper or dampers, and thus a mixture of heated air and products of combustion is caused to pass downwardly over and around the roller and onto the road surface escaping beneath the hinged flaps *n*. A baffle *s* at the front side of the furnace prevents the air from sweeping straight across the furnace, and further baffles *t*, *t*, located at suitable points 100 ensure an even distribution of the hot air and gases over the road surface below the hood.

To prevent the tar or bitumen from ad- 110

hering to the surface of the roller, means may be arranged for spraying water or steam under pressure on to the surface preferably at or near the bottom thereof.

5 Also to prevent stones or grit adhering to the surface a spring pressed scraper may be arranged at a suitable point in engagement with or closely adjacent to the roller surface.

10 The roller is maintained at a high temperature by the large volume of hot air and gases passing over it and the pressure of the heated roller on the road surface, together with the simultaneous heating of the road

15 surface, both before and behind the roller, ensures complete homogeneity of the surface and enables satisfactory work to be done under any weather conditions.

If desired one or more idle rollers parallel 20 to the roller *c* may be arranged in front of or behind the roller *c* to distribute the load, the hood being suitably extended, but for ordinary road work these are not essential.

When the roller is standing idle during 25 any temporary suspension of operations there is a danger that the roller by melting the tar or bitumen might sink into the road surface and there is preferably carried on the machine a steel or other plate of substantial dimensions which is adapted to be placed on the road surface beneath the roller under such circumstances.

I claim:—

1. A road making and repairing machine, 35 comprising in combination a running frame, a roller, means on said running frame for generating a current of hot air and gases, and means for directing said current on to said roller and on to the road surface adjacent to said roller.

2. A road making and repairing machine, 40 comprising in combination a running frame, a roller, means on said running frame for generating a current of hot air and gases, a hood enclosing the said roller and having its lower edge closely adjacent to the road sur-

face, and means for directing said current of hot air and gases into said hood.

3. A road making and repairing machine, 45 comprising in combination a running frame, a roller, means on said running frame for generating a current of hot air and gases, a hood enclosing the said roller, hinged flaps forming the lower parts of the sides of said hood and terminating closely adjacent to the 50 road surface, and means for directing said current of hot air and gases into said hood.

4. A road making and repairing machine comprising in combination a running frame, a roller, means on said running frame for generating a current of hot air and gases, a hood enclosing said roller and having its lower edge closely adjacent to the road surface, means for directing said current of hot air and gases into said hood, and baffles 60 located within said hood to distribute the hot air and gases evenly therein.

5. A road making and repairing machine, 65 comprising in combination a running frame, a power-driven roller supporting one end of said running frame, a hood enclosing said roller and extending downwardly towards the road surface, a furnace and power-driven draught-producing means on said frame, said power-driven means creating a 70 draught through said furnace, and means for directing hot air and gases from said furnace into said hood.

6. A road making and repairing machine, 75 comprising in combination a running frame, a power-driven roller supporting one end of said frame, a furnace mounted on said frame, a curved upper part to said furnace leading to a hood enclosing said roller, a power-driven fan forcing air through said furnace and into said hood, and hinged flaps forming the lower parts of the sides of said hood and terminating closely adjacent to the 80 road surface.

In testimony whereof I affix my signature.

JOHN HINES.
